MULTI-BEAM CONVERGENCE CIRCUITS**Morris D. Nelson, New York, N. Y., assignor to Radio Corporation of America, a corporation of Delaware****Application October 3, 1955, Serial No. 539,883****9 Claims. (Cl. 315—13)**

The invention relates to systems for controlling the deflection of electron beams of cathode ray tubes, and it particularly pertains to such systems in which a plurality of electron beams are deflected by common deflection circuitry.

One type of cathode ray tube, or kinescope with which the invention may be successfully used is a color kinescope of the general type described in an article "A Three-Gun Shadow-Mask Color Kinescope," by H. B. Law published in the Proceedings of the IRE, volume 39, No. 10, for October 1951 at page 1186. Part of the target electrode structure of such a tube is a luminescent screen in which different phosphor areas produce differently colored light when excited by electron beams impinging from different angles, the angle of impingement determining the particular color of the light produced. For satisfactory operation of such kinescopes, it is necessary to effect substantial convergence of the different electron beams at all points on the raster formed by deflecting the three electron beams in two mutually perpendicular directions. A general discussion of this beam convergence problem will be found in an article entitled "Deflection and Convergence in Color Kinescopes," by A. W. Friend, published in the Proceedings of the IRE, volume 39, No. 10, for October 1951 at page 1249. One type of multi-beam kinescope to which the invention particularly pertains includes a pair of magnetic pole pieces for each beam located internally of the kinescope envelope. These internally located pole pieces are energized by magnetic components arranged outside the kinescope envelope. These magnetic components may be entirely electromagnetic or they may include some permanent magnetic structure since the internally located pole pieces usually require static as well as dynamic energization. In general, it is desirable to provide such convergence means for kinescopes with the minimum of additional components.

An object of the invention is to provide improved circuitry for effecting convergence of the plurality of electron beams of a multi-beam kinescope.

Another object of the invention is to provide an improved circuitry for effecting convergence of the plurality of beams of a multi-beam kinescope with passive network elements.

According to the invention parabolic convergence current waves for application to the pole-piece exciting windings of a multi-beam kinescope are obtained by integration of pulse and sawtooth voltage waves in resistive and inductive reactance circuits. The circuit features adjustable resistance elements connected in the cathode lead of a vertical deflection wave amplifying tube which in conjunction with an inductance element provides variable amplitude parabolic voltage waves at the vertical deflection rate which are integrated upon application to the highly inductive convergence system windings to cause currents of parabolic waveform to flow therethrough. Other resistive elements connected across a center-tapped isolated winding on a vertical

2

deflection wave transformer provide variable amplitude positive or negative sawtooth voltage waves at the vertical deflection rate for tilting the parabolic waves. A voltage pulse obtained from a horizontal deflection wave amplifying circuit is applied to a plurality of series circuits each comprising an adjustable inductance element and a resistance element of low impedance with respect to that of the inductance element. The amplitude of the sawtooth voltages thus produced at the horizontal line deflection rate may be adjusted by varying the inductances in the circuits to provide variable amplitude current waves at horizontal deflection rate of parabolic waveform upon application sawtooth voltages to the highly inductive convergence system windings. A compensating capacitance element may be interposed in series with each resistance element to provide more suitable waveform and also in order to reduce the power loss by permitting the use of larger values of resistance elements. The resulting parabolic current waveform is corrected for tilt by adding a sawtooth current wave of horizontal deflection rate to the parabolic wave. Another capacitive reactance element is connected between the junction of the compensating capacitance element and the resistance element and the point at which the horizontal voltage pulse is applied to the inductance element. The two capacitive elements form a capacitive voltage divider. The other capacitance element may be adjustable in order to vary the amplitude of the sawtooth component which is added for tilting the parabolic wave. By means of a trifilar winding, interposed in the circuit to prevent the horizontal deflection rate currents from flowing in the vertical deflection wave circuits whose impedance is normally of a low value at which the horizontal frequency components would be excessively loaded, both horizontal and vertical convergence current waves flow in the same windings. The use of a trifilar winding effectively isolates the separate convergence circuits and also insures that the horizontal rate voltage pulses are initially of the same value in each of the convergence circuits despite variations in the applied voltage due to power line fluctuations and the like. Alternatively, an arrangement is suggested in which a trifilar winding on the horizontal deflection wave output transformer is used to produce the desired pulse voltages and at the same time provides choke action to keep the horizontal convergence waves out of the source of vertical convergence waves.

In order that the practical aspects of the invention may be fully appreciated, an express embodiment, given by way of example only, is described hereinafter with reference to the accompanying drawing in which:

Fig. 1 is a functional diagram of a television receiving apparatus in which the invention may be incorporated;

Fig. 2 is a cross section view of a multi-beam kinescope of the type to which the use of the invention is particularly applicable; and

Fig. 3 is a schematic diagram of an embodiment of the invention.

Referring first to Fig. 1, there is shown a functional diagram of portions of a color television receiver to which the invention is particularly adaptable, and which receiver may otherwise comprise entirely conventional circuitry. In such a receiver, color television signals appearing at an antenna are applied to a radio frequency wave amplifying circuit and the output therefrom is applied along with the wave obtained from a local beat oscillation generating circuit to a frequency changing circuit. The output of the frequency changing circuit is applied to an intermediate frequency (I.-F.) amplifier which may be one having separate channels for picture and sound signals or one in which both picture and sound signals are amplified at the same time. A video de-

modulating circuit 17 is connected at terminal 16 to the I.-F. amplifying circuit for deriving a video wave from the television signals. The detected video signals are amplified in a video frequency (V.-F.) amplifying circuit 18. Sound signals are derived from the sound I.-F. amplifying circuit, or from the demodulating circuit 17 or from the V.-F. circuit 18, for further processing in a sound I.-F. amplifying circuit, an audio frequency (A.-F.) amplifying circuit and a transducer, usually in the form of a loud speaker. The output of the V.-F. amplifying circuit is applied to a circuit 19 for converting luminance and chrominance components into proper form for application to the signal input circuitry of an image reproducing display device, or kinescope 20. The output of the video frequency amplifying circuit is also applied to synchronizing pulse separating circuit 24 to separate the synchronizing pulses from the picture signals and to separate the horizontal synchronizing pulses from the vertical. The separated vertical synchronizing pulses are applied to a vertical deflection wave generating circuit 25 and thence to a vertical deflection wave amplifying circuit 26, while the horizontal synchronizing pulses are applied to a horizontal deflection frequency oscillator and frequency control circuit 27 and thence to a horizontal deflection wave amplifying circuit 28. The high voltage and focus voltage generating circuit may be coupled to the horizontal deflection wave amplifying circuit. The vertical deflection wave amplifying circuit 26, the horizontal deflection wave amplifying circuit 28 and the high voltage and focus voltage generating circuit 29 are coupled to the kinescope 20 to supply vertical and horizontal deflection waves and focus and ulti potentials. The vertical deflection wave amplifying current 26 and the horizontal deflection wave amplifying circuit 28 are connected to a convergence wave generating circuit 30 according to the invention for generating convergence waves for dynamic convergence of individual beams of the multi-gun kinescope 20. A low voltage power supply, normally connected to the local A.-C. power lines, is arranged to furnish direct energizing potentials to all circuits. An automatic gain control amplifying distributing network is coupled to the synchronizing pulse separating circuit 24 or the video frequency demodulating circuit 17 or to the video amplifying circuit 18 to supply control potentials to the desired ones of the circuits previously mentioned. Normally the R.-F. and I.-F. amplifying circuits are at least so supplied.

The kinescope 20 may be of the same general type as that disclosed in the H. B. Law paper hereinbefore mentioned. The kinescope 20 preferably has a luminescent screen provided with a multiplicity of small phosphor areas arranged in groups and capable of producing light of the different component colors when excited by electrons. In back of and spaced from the screen there is an apertured masking electrode having an aperture for and in substantial alignment with each group of phosphor areas. The luminescent screen and the masking electrode may have planar or partially spherical surfaces; the invention being equally applicable to either form of target electrode structure.

The kinescope 20 also has a plurality of electron beams equal in number to the number of component colors in which the image is to be reproduced. Conventionally, three such electron guns, which may be entirely conventional in structure consisting of a cathode, a control electrode and a focusing electrode, are arranged substantially parallel to produce three separate electron beams by which to energize respectively blue, red and green phosphor areas of the screen of the kinescope. The kinescope 20 also contains a beam accelerating electrode, or ulti, consisting of a conductive wall coating on the inner surface of the envelope of the kinescope and extending out to the region of the target electrode structure. When these electron beams are properly converged at the target

structure, the electrons pass through the apertures of the masking electrode from different directions and impinge on different phosphor areas of each of the groups so as to produce light in the three component colors. The electrodes of the kinescope 20 may be energized in the conventional manner and the color information signals are applied so that the electron beams are modulated in intensity in accordance with the information carried by the color-representative video signals derived from the translator circuit 19. The video signal source will not be described further herein since it does not form an essential part of the invention.

Associated with the color kinescope 20 is a deflection system yoke, which may be entirely conventional and in which may be mounted two pairs of suitably placed windings electrically connected so that when properly energized, electromagnetic fields are produced to effect angular deflections of the electron beams in both the horizontal and vertical directions to scan the usual rectangular raster at the target electrode structure. Deflection waves for application to the deflection system windings are obtained from the vertical and horizontal deflection wave amplifying circuits 26 and 28 respectively.

The beam convergence system in accordance with the invention also includes a plurality of electromagnetic field producing elements arranged about the neck of the kinescope adjacent to the predeflection paths of the electron beams. An example of such construction is shown in Fig. 2 wherein three magnet assemblies 31, 32 and 33 arranged about the neck of a kinescope envelope 35. The precise location of the magnet assemblies is not necessarily indicated in Fig. 2 but it is to be understood that each of the magnet assemblies is located relative to the path of one of the electron beams to influence that one beam to the virtual exclusion of the others. The magnetic fields produced by these magnet assemblies are transverse to the associated beam paths and in a direction to move the associated beams radially relative to the longitudinal axis of the kinescope. The convergence magnet assemblies 31-33 are usually energized by a substantially unidirectional current component to effect an initial convergence of the electron beams substantially at the target electrode structure. Normally, convergence is initially made at the center of the screen, however, this initial convergence may be made at any point, for example, at one corner of the raster. In order to do this, the unidirectional energizing current component is effected in such a way that the magnet may be individually energized in different magnitudes.

The convergence magnet assemblies 31-33 are also dynamically energized by wave energy derived from suitable generating means so as to effect a variation in the magnitude of the transverse fields produced and to vary the deflection of the individual electron beams as a function of the overall deflection of the three beams. In this way suitable variations are made in the convergence angles between the various beam components in the individual beams so as to produce the desired convergence of the beams substantially at all points of the target electrode structure. All of the magnet assemblies being the same, only one will be described in detail. The magnet assembly 31 comprises a core, which may be in one piece, but is shown in two pieces 36, 37 having legs 38, 39 extending at right angles to the main body of the core. If direct current is utilized to afford static convergence, the core might conveniently be in one piece. As shown, however, the core of the magnet assembly 31 is split into two pieces 36, 37 and mounted between the core pieces in suitable recesses formed therein is a substantially cylindrical permanent magnet 40. This magnet is polarized substantially diametrically so as to present north and south poles in the two halves thereof substantially as indicated. The permanent magnet 40 may be provided with suitable adjusting facilities, such as a screw driver slot, formed in one or both ends. The rotation of the permanent magnet 40 between the core sections 36, 37 enables the strength of

the permanent magnetic field produced to be adjusted in both magnetic and polarity. Windings 41, 42 are mounted on the legs of the core pieces, although alternatively the windings may be wound as a unitary structure and mounted on the main body portion of the core. A set of pole pieces 43, 44 is provided internally of the kinescope envelope 35 for each of the convergence magnet assemblies. The internal pole pieces 43, 44 are arranged to increase the effectiveness of the associated magnet assemblies by decreasing the reluctance of the magnetic circuit and considerably improving the flux distribution of the field produced between the pole pieces. The convergence magnet assemblies 31-33 produce fields which in the vicinity of the electron beams associated therewith are substantially transverse to the axis of the kinescope. The electron beam associated with each of the magnet assemblies may be readily moved toward or away from the longitudinal axis by adjusting the amount of magnetic flux in the respective assemblies 31-33. The direction and magnitude of such beam movement is controlled by the energization of the windings 41, 42 and rotation of the permanent magnet 40.

The convergence magnet assemblies 31-33 may be energized by means of the circuit arrangement shown in Fig. 3. The convergence magnet assemblies may be substantially identical, and may be energized by substantially identical circuits. Therefore, the description will be limited to the particular circuits by which the windings 41 and 42 of the convergence magnet assembly 31 are energized, it being understood that the same description applies equally as well to the circuits illustrated for energizing the other convergence magnet windings except where specifically noted.

Referring to Fig. 3, synchronizing pulses of vertical deflection rate are applied at input terminals 51, 52 to a vertical deflection wave oscillator tube 54 for producing a sawtooth voltage wave across a charging capacitor 56 connected in series with a peaking resistor 57. The peaked sawtooth voltage wave is applied by way of connections including a coupling capacitor 58 to a vertical deflection wave amplifying tube 59. Vertical sawtooth current waves are induced in a vertical deflection wave output transformer 60 by a primary winding 62 connected in the anode circuit of the vertical amplifier tube 59. The sawtooth deflection wave appearing across a secondary winding 64 is applied to a vertical deflection system winding comprising sections 66, 67. No provisions are shown in the circuit for deflection centering of the scanning beams, but conventional centering current circuitry may be employed in known manner. A sawtooth voltage wave at horizontal deflection rate is applied at input terminals 71, 72 of the horizontal amplifying tube 74. A sawtooth current wave is induced by the connections to the amplifying tube 74 in a winding 76 of the horizontal deflection wave output transformer 73. The deflection pulse voltage and sawtooth current wave appearing in the output portion of the winding 76 is applied to a horizontal deflection system winding comprising two sections 81, 82 the latter of which is shunted by an anti-ringing capacitor 83. Again no centering provisions have been shown, but these may be readily supplied according to the known art.

A sawtooth voltage wave at the vertical deflection rate appears across an unbypassed resistance element 86 in the cathode lead of the vertical deflection wave amplifying tube 59. This resistance element 86 is used to return the cathode to the point of reference potential, shown as ground, and to provide a sawtooth voltage wave for producing the vertical convergence parabolic current wave. An inductance element 88 is connected between the unbypassed resistance element 86 and a plurality of variably tapped resistance elements or potentiometers 91, there being one such resistance element for each circuit desired. In the example shown, there is a potentiometer 91R for the red controlling electron beam, another potentiometer

91G for the green controlling electron beam, and a further potentiometer 91B for the blue controlling electron beam. Hereinafter, the suffixes R, G and B are dropped from the reference numerals when considering the general aspects of the component circuits, and it should be understood that the description with reference by means of a general reference number applies equally well to the specific component circuits. Due to partial integration brought about by the inductance element 88, the potential across the parabolic convergence voltage level setting potentiometers 91 very closely approximates a parabola at the vertical deflection rate. Movement of the arms 92 of the potentiometers 91 serves to adjust the amplitude of the parabolic voltage components available for converging the individual electron beams in the vertical direction.

By use of the inductor 88 for partially integrating the vertical sawtooth wave, the expense of a large electrolytic capacitor previously used for this purpose is eliminated. More important is that the initial operation and the stability of the circuit is greatly improved because the manufacturing tolerances of inductors are closer than that of electrolytic capacitors. The inductance of inductors does not tend to vary with age, as does the capacitance of electrolytic capacitors. Furthermore the integrating inductor 88 has a negligible effect on the output vertical deflection wave, which means that a less expensive vertical output stage may be used to secure the desired results.

By means of variably tapped resistance elements or potentiometers 94R, 94G and 94B connected in parallel across a center tapped secondary winding 104 of the vertical deflection wave output transformer 60, positive or negative sawtooth waveforms at the vertical deflection rate may be obtained by movements of the taps or arms 95 respectively of the resistance elements or potentiometers 94. At an intermediate position of each potentiometer arm, the potential from the arm to the neutral point of reference potential, shown as ground, is zero.

Moving the potentiometer arm to either side of neutral causes either a positive or negative sawtooth wave to appear between the arm and the point of reference potential of amplitude proportional to the degree of movement of the arm. Each of the convergence windings is divided into two sections 41, 42 as shown in Fig. 2. Referring again to Fig. 3, the plurality of convergence pole-piece exciting winding sections are individually connected between the arms 92 of the parabola amplitude controlling potentiometers 91 and the arms 95 of the tilt controlling potentiometers 94, by means of a trifilar wound inductor 100 having conductors 101-103, a plurality of inductors 104R, 104G and 104B. The inductors 100 and 104 are more resistive than inductive at the vertical frequency as they are intended for operation on the horizontal current components, so that the sawtooth vertical deflection frequency voltages are unaffected by the horizontal components but are integrated by the substantially high inductance of the convergence system windings 41, 42 to produce parabolic current flow. The amplitudes of these parabolic components are determined by the positions of the arms 92 on the parabola adjusting potentiometers 91.

A color purity magnet is used with tri-color kinescopes of the type mentioned hereinbefore. This magnet operates by directing the three electron beams across the longitudinal axis of the kinescope and this beam movement, together with some component tolerances, makes tilting necessary. The parabolic waves are tilted, or shifted so that the minimum amplitude points are either toward the beginning or the end of the waves, by positioning the arms 95 on the sawtooth wave amplitude setting potentiometers 94. For this reason these potentiometers 94 are usually termed "tilt" controls. The approximately parabolic vertical voltages are somewhat still further integrated by the inductance of the convergence system

windings sections and the inductors 104 to yield the desired vertical frequency parabolic current waves.

With tri-colored kinescopes of the type described, the electron guns are mechanically tilted toward the central axis of the kinescope so that the individual beams virtually converge at the center of the phosphor screen. However, because of manufacturing tolerances, a static component of magnetic field is necessary to set the beam direction of each gun precisely. This field is obtained by means of the rotatable permanent magnets 40 in the convergence coil assemblies 31 as shown in Fig. 2. The field required is a function of the error and the square root of the ulti potential, the latter of which follows the power line voltage in shunt tube high voltage regulating systems. Both the vertical and the horizontal dynamic convergence voltages are applied to the convergence system windings 41, 42 for alternating current flow only. When the components of magnetic field these voltages produce are added to the static component required for center convergence as previously adjusted, the total field when scanning the center of the raster will be in error by an amount equal to the instantaneous value of the dynamic convergence voltage. This error is corrected by adding a compensating field of equal value and opposite sign by means of a resistance element 106 which is connected to a source of intermediate potential obtained from the same low voltage rectifier that supplies the circuits developing the dynamic components; that is the horizontal and vertical deflection wave translating stages whose outputs vary directly with the power line voltage. In the circuit shown in Fig. 3 the compensating field varies in the same manner as the dynamic fields so that for normal power line voltage variations, there is high degree of tracking over the raster, resulting in excellent beam convergence.

According to the invention parabolic current waveforms are also utilized for horizontal convergence of the three beams of a tri-color kinescope, thereby improving the operation over that of circuits in which horizontal convergence is obtained by modified sine wave currents. A voltage pulse wave of horizontal recurrence rate is applied to a series circuit comprising an inductive element and a resistive element of lower impedance than that of the inductive element. The series combination is therefore predominately inductive and the voltage across the series circuit is therefore approximately sawtooth in shape, being an integral of the applied pulse voltage. The voltage developed across the resistance element is similarly sawtooth in shape. By placing the convergence system windings in shunt with the resistance element, the sawtooth voltage wave is integrated to produce parabolic current wave through the highly inductive convergence system windings. If the impedance of the convergence system winding is much larger than that of the resistance element, the sawtooth voltage wave shape will be but slightly affected. By interposing a compensating capacitive element in the series with the resistance element, the resulting sawtooth voltage wave will be symmetrical and slightly S-shaped. This latter arrangement provides a more perfect parabolic current waveform in the convergence winding and permits the use of larger values of resistance elements. This results in lower power loss which is advantageous since the horizontal deflection frequency power dissipated in the convergence system shows up as a loss of available regulated high voltage current, which is conventionally derived from the horizontal deflection stage.

As shown in Fig. 3, a voltage pulse wave of horizontal deflection frequency and positive going with respect to the point of reference potential, shown as ground, is obtained by means of a coupling capacitor 107 and applied directly across the variable inductance element 104R which is connected in series with a shunting resistor 108R

and a compensating capacitor 109R. As shown, the horizontal voltage pulse wave is the same wave that is conventionally applied by means of a capacitive element to the automatic gain control circuit. However, this pulse wave may be obtained from any other point in the horizontal deflection wave output circuit that such a gating pulse wave is obtained. In addition to acting as a choke to prevent horizontal frequency components from entering the source of vertical frequency components, the trifilar winding 100 serves as a pulse wave transformer to induce the horizontal voltage pulse wave which is impressed across the winding 101 into the trifilar windings 102 and 103 for application to the other convergence circuits comprising the variable inductance elements 104G, 104B, shunting resistors 108G and 108B, and compensating capacitors 109G and 109B. Alternately, an isolated trifilar winding on the horizontal deflection wave output transformer would serve as well and obviate the need for any coupling capacitor. Each conductor of the trifilar winding would still serve as a path for vertical current components just as in the choke arrangement.

The convergence system windings sections 41 are effectively in shunt at the horizontal deflection frequency with the shunting resistors 108 through a path including the field compensating resistors 106 and the low voltage rectifier (not shown), the negative pole of which is conventionally maintained at ground.

The horizontal frequency parabolic components are tilted by adding a sawtooth component to the current in the convergence system windings 41, 42 by means of tilt controlling capacitive elements 114. The sawtooth components for the red and green convergence system windings 41R, 42R, 41G, 42G are obtained by means of a coupling capacitor 116 connected to the trifilar winding 101 of the trifilar choke 100, while that for the blue convergence system winding is shown with the tilt controlling capacitance element 114B connected directly to the trifilar winding 103. Since only capacitive elements are used, such "cross-connections" afford many cost reducing alternatives without detracting from the performance of the circuit in any way. The effect of adding the sawtooth component to the parabola is to increase the current on one side of the raster and decrease it on the other. By reversing the sawtooth polarity the action can be reversed. The same type of action occurs if the parabolic current wave is shifted in time with respect to the deflection and blanking period. This is effected by adding the pulse voltage wave required for tilting to the sawtooth voltage wave used for generating the parabolic wave. The overall result is an initially delayed sawtooth voltage wave which upon integration results in a tilted parabolic wave, requiring compensating tilt in the opposite direction. The degree of tilt is controlled by the amount of pulse added. The capacitive elements 109, 116, and 114, form voltage dividers by which the adjustment of the adjustable capacitive element 114 in each case determines the amount of pulse added to provide the required tilt.

Since a horizontal frequency convergence component required by the blue gun of some tri-color kinescopes as conventionally operated is larger than that required by the red and green guns, the impedance of the blue convergence system windings 41B, 42B may be made lower so that like voltages can be used for the three deflection system windings. In addition the parallel network comprising the capacitor 110 and the shunt resistor 111 may be added, as shown, to the blue convergence windings circuit since the static compensating current is higher due to the greater dynamic convergence voltage component.

Those skilled in the art will determine the values of components to be used in various applications of the invention from the teachings herein, however, the values of pertinent components listed below which were used in a successfully operated color television receiver having

convergence systems as shown in Fig. 3, are given as a guide in the practice of the invention.

Ref. No.	Component	Type or Value
20	Tri-color Kinescope	21AXP22.
41, 42	Convergence system winding: (red, green) (blue only)	660 mfh. 120 mfh.
54, 59	Vertical oscillator and amplifier tubes	6BL7.
74	Horizontal amplifier tube	6CD6.
78	Horizontal pulse wave source	800 to ground.
86	Cathode resistor	270 ohms.
87	Vertical Linearity Control	0-1 ko.
88	Vertical Integrating Inductor	2.0 h.
91	Vertical Parabola Control	0-1 ko.
94	Vertical Tilt Control	0-100 ohms.
98	Vertical Tilt Winding	± 100 v.-to-ground.
100	Trifilar choke	50 mfh.
104	Horizontal Integrating Inductors	100-600 mfh.
105	Blocking capacitors	50 mfd.
106	Dropping resistors	82 kohms.

116	Series capacitor (red and green only)	560 mfd.

Power supplied delivered approximately 400 volts between the points marked "+" and ground, with 200 volts being delivered at the intermediate points marked "+:."

The invention claimed is:

1. A beam convergence circuit arrangement for multi-beam kinescope the electron beams of which are deflected in two directions normal with respect to each other, including a plurality of convergence windings through which currents of substantially parabolic waveform of frequency corresponding to electron beam deflection in one of said directions are desired, a plurality of series circuits each comprising an inductance element and a resistance element connected in series, means to apply a voltage pulse train of recurrence rate corresponding to said deflection in said one direction across said series circuits, and means to couple said windings individually across said resistance elements in such manner that the voltage produced across each resistance element by said pulse train is impressed upon its associated winding.

2. A beam convergence circuit arrangement for multi-beam kinescope the electron beams of which are deflected in two directions normal with respect to each other, including a plurality of convergence windings through which currents of substantially parabolic waveform of frequency corresponding to electron beam deflections in one of said directions are desired, a plurality of series circuits each comprising an inductance element and a resistance element connected in series, means to apply a voltage pulse train of recurrence rate corresponding to said deflection in said one direction across said series circuits, and means including capacitive reactance elements to couple said windings individually across said resistance elements.

3. A beam convergence circuit arrangement for an internal convergence pole-piece type multi-beam kinescope the electron beams of which are deflected in two directions normal with respect to each other, including a plurality of convergence pole-piece exciting windings through which currents of substantially parabolic waveform of frequency corresponding to electron beam deflection in one of said directions are desired, a plurality of series circuits each comprising an adjustable inductance element and a resistance element connected in series, means to apply a voltage pulse train of recurrence rate corresponding to said deflection in said one direction across said series circuits, and means including capacitive reactance elements to couple said windings individually across said resistance elements, the amplitude of said parabolic current waveform being varied by adjustment of said inductance element.

4. A beam convergence circuit arrangement for an internal convergence pole-piece type multi-beam kinescope

the electron beams of which are deflected in two directions normal with respect to each other, including a plurality of convergence pole-piece exciting windings through which currents of substantially parabolic waveform of frequency corresponding to electron beam deflection in one of said directions are desired, a plurality of series circuits each comprising an inductance element and a resistance element connected in series, means to apply a voltage pulse train of recurrence rate corresponding to said deflection in said one direction across said series circuits, means including capacitive reactance elements to couple said windings individually across said resistance elements, and means to apply a portion of said voltage pulse train across each of said windings.

5. A beam convergence circuit arrangement for an internal convergence pole-piece type multi-beam kinescope the electron beams of which are deflected in two directions normal with respect to each other, including a plurality of convergence pole-piece exciting windings through which a current of substantially parabolic waveform of frequency corresponding to electron beam deflection in one of said directions is desired, a plurality of series circuits each comprising an inductance element and a resistance element connected in series, means to apply a pulse voltage train of recurrence rate corresponding to said deflection in said one direction across said series circuits, means including capacitive reactance elements individually to couple said windings across said resistance elements, and means including other capacitive reactance elements individually operative to conjunction with the first said capacitive reactance elements to apply a portion of said pulse voltage train individually to said windings.

6. A beam convergence circuit arrangement for an internal convergence pole-piece type multi-beam kinescope the electron beams of which are deflected in two directions normal with respect to each other, including a plurality of convergence pole-piece exciting windings through which a current of substantially parabolic waveform of frequency corresponding to electron beam deflection in one of said directions is desired, a plurality of series circuits each comprising an adjustable inductance element and a resistance element connected in series, means to apply a pulse voltage train of recurrence rate corresponding to said deflection in said one direction across said series circuits, means including capacitive reactance elements individually to couple said windings across said resistance elements, and means including adjustable capacitance elements individually operative in conjunction with the first said capacitive reactance elements to apply a portion of said pulse voltage train individually to said windings, the amplitude of said parabolic current waveform being varied by adjustment of said inductance element and the tilt being varied by adjustment of said capacitance elements.

7. A beam convergence circuit arrangement for an internal convergence pole-piece type multi-beam kinescope the electron beams of which are deflected in two directions normal with respect to each other, including a plurality of convergence pole-piece exciting windings through which currents of substantially parabolic waveforms of frequency corresponding to electron beam deflection in both of said directions are desired, a plurality of series circuits each comprising an inductance element and a resistance element connected in series, means including a trifilar winding individually to apply a voltage pulse train of recurrence rate corresponding to said deflection in said one direction across said series circuits, means including capacitive reactance elements individually to couple said windings across said resistance elements, means including adjustable capacitive reactance elements to apply a portion of said voltage pulse train across said windings, an inductive reactance element and a plurality of variably tapped resistance elements connected in common to said inductive reactance element, means to apply a sawtooth wave of recurrence rate corresponding to

deflection in the other direction between said inductive reactance element and each of said variably tapped resistance elements to produce a substantially parabolic voltage wave across the last said elements, a plurality of variably tapped resistive elements having taps individually connected to said trifilar winding, means to apply a pulse train recurrence rate corresponding to deflection in said other directions across said resistive elements, and means coupling said convergence windings to the taps of said variably tapped resistance elements.

8. A beam convergence circuit arrangement for a multi-beam kinescope, comprising a vertical deflection wave circuit including an output transformer having a convergence winding with an intermediate tap being electrically at a point of fixed reference potential and midway between the terminals of said winding, and an amplifying electron discharge tube having anode and cathode electrodes connected to the primary winding of said transformer through an unbypassed resistance element, a plurality of variably tapped resistive elements connected between said terminals of said convergence winding, an inductor having one terminal connected to the one terminal of said resistance element, a plurality of variably tapped resistance elements connected between the other terminal of said inductor and said point of fixed reference potential, a horizontal deflection wave output transformer having a winding, a trifilar choke having plurality of conductors having terminals connected individually to the taps of said resistance elements and being coupled to a point on said horizontal transformer winding, an adjustable inductor, a resistor and a capacitor connected in series with each of the conductors of said trifilar choke, adjustable capacitors connected across each of the series circuits comprising said adjustable inductor and resistor,

a plurality of convergence system windings connected individually between junctions of said adjustable inductors and resistors and the taps of said resistance elements by blocking capacitors, connections between each of said capacitors in said series circuits and the junctions between said blocking capacitors and said convergence windings, and resistors connected between a point of fixed energizing potential and the individual junctions of said blocking capacitors and said convergence system windings.

9. A beam convergence circuit arrangement for multi-beam kinescope the electron beams of which are deflected in two directions normal with respect to each other, including a plurality of convergence windings through which currents of substantially parabolic waveform of frequency corresponding to electron beam deflection in one of said directions are desired, a plurality of series circuits each comprising an inductance element and a resistance element connected in series, means to apply a voltage pulse train of recurrence rate corresponding to said deflection in said one direction across said series circuits to produce substantially sawtooth voltage waves across said resistance elements, and means to couple said windings individually across said resistance elements in such manner that said sawtooth voltage waves appearing across said resistive elements serve to induce substantially parabolic current waves in said windings.
